TRACK CIRCUIT

Bernard E. O'Hagan, Swissvale, Pa., assignor to
The Union Switch & Signal Company, Swiss-
vale, Pa., a corporation of Pennsylvania

Application October 17, 1934, Serial No. 748,675

16 Claims. (Cl. 246—34)

My invention relates to railway track circuit apparatus, and more specifically to apparatus for increasing the shunting sensitivity of track circuits.

5 I will describe several forms of track circuit apparatus embodying my invention, and will then point out the novel features thereof in claims.

10 Fig. 1 of the accompanying drawing is a dia-
grammatic view showing one form of apparatus
embodying my invention. Figs. 2 and 3 are frag-
mentary diagrammatic views illustrating modi-
fied forms of a portion of the apparatus shown
in Fig. 1, and each also embodying my invention.

15 Similar reference characters refer to similar
parts in each of the several views.

Referring first to Fig. 1, the reference char-
acters 1 and 2 designate the rails of a section
of railway track electrically isolated from the
20 adjoining portions of the track by insulated
joints 10. At one end of the section is a trans-
former T and a reactor R. The primary 3 of
the transformer T is connected to a suitable
25 source of alternating current, the terminals of
which are designated X and O. The secondary
4 of the transformer T is connected across the
rails to supply current, through the windings 6
30 and 7 of the reactor R, to a track relay P which
is connected across the rails at the other end of
the section. The winding 8 of the reactor R is
connected to the direct current terminals of a
35 rectifier Q, the alternating current terminals of
which are connected to the rails in multiple with
the track relay P.

35 The reactor R comprises a continuous mag-
netic core 5 having a center leg and two outer
legs. The outer legs are provided with the wind-
ings 6 and 7 so connected that the fluxes in-
duced in the core 5 by their energization is addi-
40 tive; therefore, no current is induced in the
winding 8 which is wound about the center leg.
The direct current, from the rectifier Q, flowing
in winding 8 serves to create a flux which varies
the permeability of the magnetic core 5 whereby
45 the reactance of the windings 6 and 7 can be
made variable.

When the track is shunted by a train, the
50 current supplied to the rectifier Q and the track
relay P is reduced; so that the direct current
flowing in the winding 8 is reduced, and this
causes a relatively large increase in the reactance
of windings 6 and 7. The increased reactance
55 in windings 6 and 7 still further reduces the
current available at the rectifier Q and the
track relay P.

Thus it will be seen that I have provided a
means, when the track is shunted, for causing
an increase in the impedance between the trans-
former T and the rails, and, consequently, a
5 relatively larger reduction in the amount of cur-
rent flowing through the winding of track relay
P, than would obtain if the usual current limit-
ing reactor were used.

Since the shunting sensitivity of a track cir-
cuit is largely determined by the amount of
10 impedance in series with the source of track cir-
cuit current, the marked advantage of the ap-
paratus shown in Fig. 1 is obvious. A high
impedance in series with the source of track
15 circuit current causes a relatively large potential
drop when the track is occupied, so that the
voltage across the track relay is greatly reduced,
whereupon positive release of the relay is assured.

From the foregoing explanation, it is clear
20 that a train shunt of much higher resistance
will be effective in causing relay P to release if
the reactor R is used, than if the usual type of
reactor is employed.

If it is desired to regulate the flow of current
25 through the rectifier Q, a transformer TA hav-
ing a variable secondary as illustrated in Fig. 2,
or a variable resistor S as illustrated in Fig. 3,
may be used. Otherwise, the apparatus shown
in Figs. 2 and 3 is the same as that shown in
Fig. 1.

Although I have herein shown and described
only a few forms of apparatus embodying my
invention, it is understood that various changes
and modifications may be made therein within
the scope of the appended claims without de-
parting from the spirit and scope of my inven-
tion.

Having thus described my invention, what I
claim is:

1. In combination, a section of railway track, 40
a source of track circuit current connected
across the rails of said section, a track relay
receiving current from the rails of said section,
a reactor having a main winding connected be-
tween said source and one rail of said section, 45
an auxiliary winding for said reactor for setting
up in the reactor a flux for regulating the cur-
rent flowing through said main winding, and
means including a rectifier connected across the
rails of said section for supplying a variable 50
amount of current to said auxiliary winding to
govern the amount of current received by said
relay in response to traffic conditions in said
section.

2. In combination, a section of railway track; 55

a track circuit for said section including the two rails of said track, a source of current connected across said rails at one end of the section, a track relay connected across the rails at the 5 other end of the section, and a reactor having a main winding connected between said source and one rail of said section; and an auxiliary winding for said reactor receiving current from the rails of said section for setting up in said reactor 10 a flux for regulating the current flowing through said main winding to improve the shunting sensitivity of said track circuit when the section is occupied by a train.

3. In combination, a section of railway track, 15 a source of track circuit current connected across the rails of said section, a track relay receiving current from the rails of said section, a reactor having a main winding connected between said source and one rail of said section, an auxiliary winding for said reactor for setting up 20 in the reactor a flux for regulating the current flowing through said main winding, means including a rectifier for supplying current to said auxiliary winding, and means including a transformer having its primary connected across the 25 rails of said section for supplying a variable amount of current to said rectifier in response to traffic conditions in the section for governing the amount of current received by said relay.

30 4. In combination, a section of railway track, a source of track circuit current connected across the rails of said section, a track relay receiving current from the rails of said section, a reactor having a main winding connected between said 35 source and one rail of said section, an auxiliary winding for said reactor for setting up in the reactor a flux for regulating the current flowing through said main winding, means controlled by traffic conditions in said section and including a rectifier receiving current from the rails of said 40 section for supplying a variable amount of current to said auxiliary winding according as said section is occupied or unoccupied, thereby governing the amount of current received by said 45 relay, and a variable resistor for limiting the amount of current received by said rectifier.

5. In combination, a section of railway track, a source of track circuit current connected across the rails of said section, a track relay receiving 50 current from the rails of said section, a reactor having a main winding connected between said source and one rail of said section and an auxiliary winding for setting up in the reactor a flux for regulating the current flowing through 55 said main winding, means controlled by traffic conditions in said section and including a rectifier receiving current from the rails of said section for supplying a variable amount of current to said auxiliary winding according as said section 60 is occupied or unoccupied, thereby governing the amount of current received by said relay, and means not responsive to traffic conditions for regulating the amount of current received by said rectifier.

65 6. In combination, a section of railway track, a source of alternating track circuit current connected across the rails of said section, a track relay receiving current from the rails of said section, a reactor having a main winding 70 connected between said source and one rail of said section, an auxiliary winding for said reactor serving when energized by direct current to set up in the reactor a flux for regulating the current flowing through said main winding, and 75 means controlled by traffic conditions in said

section and including a rectifier receiving current from the rails of said section for supplying a variable amount of direct current to said auxiliary winding to improve the shunting sensitivity of said relay when said section is occupied by a train. 5

7. In combination, a section of railway track, a source of track circuit current connected across the rails of said section, a track relay receiving current from the rails of said section, a three-legged reactor having a main winding comprising a coil on each outer leg connected in series said main winding being interposed between said source and one rail of said section, an auxiliary winding for said reactor comprising a coil on the 15 third leg thereof for setting up in the reactor a flux for regulating the current flowing through the main winding, and means responsive to traffic conditions in said section for supplying a variable amount of current to said auxiliary 20 winding to govern the amount of current received by said relay in accordance with the occupied or unoccupied condition of said section.

8. In combination, a section of railway track, a source of track circuit current connected 25 across the rails of said section, a track relay receiving current from the rails of said section, a three-legged reactor having a main winding comprising a coil on each outer leg so connected that no flux is set up in the third leg 30 from the main winding, said main winding being interposed between said source and one rail of said section, an auxiliary winding comprising a coil on the third leg for setting up in the reactor a flux for regulating the current flowing through 35 the main winding, and means responsive to traffic conditions in said section for supplying a variable amount of current to said auxiliary winding to govern the amount of current received by said relay in accordance with the occupied or unoccupied condition of said section. 40

9. In combination, a section of railway track, a source of track circuit current connected across the rails of said section, a track relay receiving current from the rails of said section, a three-legged reactor having a main winding comprising a coil on each outer leg so connected that no flux is set up in the third leg 45 from the main winding, said main winding being interposed between said source and one rail of said section, an auxiliary winding comprising a coil on the third leg for setting up in the reactor a flux for regulating the current flowing through the main winding, and means including a rectifier connected across the rails 50 of said section for supplying a variable amount of current to said auxiliary winding to govern the amount of current received by said relay in response to traffic conditions in said section. 55

10. In combination with a section of railway track, a source of periodic current, means for connecting said source across the traffic rails of the section including a first winding of a reactor having a magnetizable core, a traffic 60 governing relay, means adapted to receive periodic current from the traffic rails for energizing said relay, other means adapted to receive periodic current from the traffic rails of the section including an asymmetric unit for 65 converting the periodic current into unidirectional current, and means energized from the output of said asymmetric unit including a second winding of said reactor and controlled by traffic conditions in said section for governing the 70 75

flux in the core of the reactor in accordance with the occupied or unoccupied condition of said section.

11. In combination with a section of railway track, a source of periodic current, means for connecting said source across the traffic rails of the section including a first winding of a reactor having a magnetizable core, a traffic governing relay, means adapted to receive periodic current from the traffic rails for energizing said relay, other means adapted to receive periodic current from the traffic rails of the section including an asymmetric unit for converting the periodic current into unidirectional current, and means energized from the output of said asymmetric unit including a second winding of the reactor and controlled by traffic conditions in said section for varying the permeability of the core of said reactor to control the periodic current supplied to the traffic rails in accordance with the occupied or unoccupied condition of said section.

12. In combination with a section of railway track, a source of periodic current, means for connecting said source across the traffic rails of the section including a first winding of a reactor having a magnetizable core, a traffic governing relay, means adapted to receive periodic current from the traffic rails for energizing said relay, other means adapted to receive periodic current from the traffic rails of the section including an asymmetric unit for converting the periodic current into unidirectional current, and means connected with the output of said asymmetric unit including a second winding of the reactor for governing the flux in the core of the reactor whereby the reactance of said first winding is controlled in accordance with the presence or absence of a train in said section.

13. In combination with a section of railway track, a source of periodic current, means for connecting said source across the traffic rails of the section including a first winding of a reactor having a magnetizable core, a second winding mounted on the core of said reactor, circuit means including a source of direct current for energizing said second winding to create a steady magnetic flux for determining the reactance of said first winding, means governed by traffic conditions of said section for controlling said circuit means whereby the voltage of the periodic current supplied across the traffic rails is varied in accordance with the presence or absence of a train in said section, and receiving means connected across the traffic rails of the section including an electroresponsive device effectively influenced by the periodic current.

14. In combination with a section of railway track, a source of periodic current, a reactor having a magnetizable core provided with a center and two outside magnetizable legs, means

for connecting said source across the traffic rails of the section including a first and a second winding mounted on the outside legs respectively and arranged in such a manner that magnetomotive forces created thereby are additive, a third winding mounted on the center leg, circuit means including a source of direct current for energizing said third winding to create a steady magnetic flux for determining the reactance of said first and second windings, traffic controlled means responsive to a train entering said section for controlling said circuit means whereby the voltage of the periodic current supplied to the traffic rails is varied in accordance with the presence or absence of a train in said section, and receiving means connected across the traffic rails of the section including an electroresponsive device effectively influenced by the periodic current.

15. In combination with a section of railway track, a source of periodic current, a reactor having a magnetizable core provided with a center and two outside legs, means for connecting said source across the traffic rails including a first and a second winding mounted on the outside legs respectively and arranged in such a manner that magnetomotive forces created thereby are additive, a third winding mounted on the center leg of the reactor, a first means receiving periodic current from the traffic rails of the section including the input terminals of a full-wave rectifier, means including the output terminals of said rectifier for supplying unidirectional current to said third winding for controlling the permeability of the core of said reactor to govern the periodic current supplied to said traffic rails, and a second means receiving periodic current from the traffic rails including a traffic governing electroresponsive device.

16. In combination with a section of railway track, a source of periodic current, a reactor having a magnetizable core provided with a center and two outside magnetizable legs, means for connecting said source across the traffic rails at one end of the section including a first and a second winding mounted on the outside legs respectively and arranged in such a manner that magnetomotive forces created thereby are additive, a third winding mounted on said center leg, circuit means including a source of direct current for energizing said third winding to create a steady magnetic flux for determining the reactance of said first and second windings and thereby control the periodic current, receiving means connected across the traffic rails at the other end of the section to receive the periodic current, a traffic governing electroresponsive device controlled by said receiving means, and traffic controlled means responsive to a train entering said section for controlling said circuit means.

BERNARD E. O'HAGAN.
